CENTERLESS GRINDER

Daniel C. Hughes, Nutley, N.J., assignor to Royal Master Grinders, Inc., Riverdale, N.J., a corporation of New Jersey

Filed Apr. 24, 1961, Ser. No. 104,929
 11 Claims. (Cl. 51—103)

The present invention relates to abrading or grinding machines, and, more particularly, to centerless grinders of the plunge-feed type having improved mechanism for feeding the work and controlling the grinding thereof.

The present invention is primarily concerned with, but not restricted to, plunge-feed centerless grinders for rapidly producing one or more relatively small parts which are generally circular in cross-section. Such machines generally comprise a work wheel or grinding wheel and regulating or feeding wheel for receiving the work therebetween, a work rest for supporting the work between the wheels, a slidably mounted ram on which the regulating wheel is mounted, and plunge-feed mechanism for reciprocating the ram to move the regulatory wheel thereon towards and away from the work wheel. Since numerous parts of various shapes and sizes are to be produced on such machines, it is necessary to adjust the speed of movement and the dwell time of the ram having the regulating wheel thereon in order to properly feed, grind and release the work.

Heretofore, grinding machines of this general type have been proposed but never met with the commercial success expected thereof because the plunge-feed mechanism was unduly complicated, because they did not provide for the aforementioned adjustments, and because they failed to take into account other considerations involved where a machine was required to produce a large variety of parts.

Accordingly, an object of the present invention is to provide a centerless grinder of the plunge-feed type which is not subject to the foregoing difficulties and disadvantages.

Another object is to provide such a grinder having an extremely simple and sturdy plunge-feed mechanism.

Another object is to provide such a plunge-feed mechanism which can be adjusted very accurately to predetermine the speed and the length of the stroke of the ram and its dwell time in both its inner and outer positions.

Another object is to provide such a plunge-feed mechanism which can be operated through a single cycle while the machine is being adjusted for grinding a particular part and can be switched over for repeated cycling and mass production after such adjustments have been made.

Another object is to provide such plunge-feed mechanism which can be installed on grinders already in the field or newly manufactured grinders.

A further object is to accomplish the foregoing in a practical, reliable and economical manner.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawings, forming a part of the specification, wherein:

FIG. 1 is a more or less schematic plan view of a centerless grinder in accordance with the present invention illustrating the relationship of the work wheel, the work rest, the regulating wheel, the ram and the plunge-feed mechanism.

FIG. 2 is an enlarged end view of the plunge-feed mechanism as seen from the front of the grinder.

2

FIG. 3 is a sectional view taken along the line 3—3 on FIG. 2 illustrating the driving connection between the ram and the plunge-feed mechanism.

5 FIG. 4 is a sectional view taken along the line 4—4 on FIG. 3 illustrating additional details of the driving connection.

FIG. 5 is a diagrammatic sectional view of a speed control device for a fluid pressure operated motor which drives the plunge-feed mechanism.

10 FIG. 6 is a wiring diagram of the electrical control network for the motor.

Referring now to FIG. 1 of the drawings in detail, there is shown a centerless grinder which generally comprises a base or stand 10 having a platform 11 on the top thereof, a work wheel 12 mounted on and journaled for rotation at the back of the platform, a longitudinal slide 14 on the platform at the intermediate portion thereof, a ram 15 slidably mounted for movement on the slide, a regulating wheel 16 mounted and journaled for rotation on the ram and facing the work wheel, a work rest 17 between the wheels and adjacent the work wheel for initially supporting the work with its axis of rotation just above a plane passing through the axes of rotation of the wheels in the conventional manner, and plunge-feed mechanism 18 for reciprocating the ram in the manner as described hereinafter at the front of the platform.

15 Conventional drive mechanism (not shown) is provided for effecting rotation of the work wheel 12 and the regulating wheel 16 which includes a motor and gearing adapted to be mounted within the base or stand 10. Also, conventional automatic work feeding mechanisms (not shown) may be provided for delivering the work to the work rest 17 or the work may be fed manually to the wheels.

20 As shown in FIGS. 2, 3 and 4, the plunge-feed mechanism 18 and its driving connection for reciprocating the ram 15 generally comprises a fluid pressure operated motor 19, such as a reversible air motor operable by factory air at about 80 p.s.i., a cross-slide 20 for a gear rack 21 which is driven by the motor 19, an annular member such as a spur gear 22 in mesh with the rack and journaled for rotation in a fixed position to prevent movement longitudinally with respect to the platform 11, the gear 22 having a screw threaded central opening 24, a shaft 25 having one end secured to the ram 15 and provided with a screw threaded portion 26, and a screw sleeve 23 threaded through the opening 24 and about the portion 26.

25 The cross-slide 20 comprises a sleeve section 27 slidably mounted by bushings 28 on a fixed rod 29 mounted at its ends on the platform, a carriage section 30 having the gear rack 21 at the underside thereof and having a pair of upper and lower spaced rollers 31 at each end, and a rail 32 parallel to the rod 29 and mounted on the platform and having a horizontal flange 34 engaged at the top and bottom by the rollers 31.

30 The spur gear 22 is journaled for rotation in a block 35 by a bearing 36, and the outer end of the shaft 25 is slidably mounted in a bushing 37 in the block 35. The outer end of the gear 21 has a handwheel 38 thereon (FIG. 1) for effecting manual movement of the ram 15 while setting up the machine to determine the end points of movement of the regulating wheels.

35 The gear teeth of the rack 21 and the gear 22 and the threads of the opening 24 and the screw sleeve 23 preferably are ratioed to effect movement of the ram back and forth about three eighths of an inch upon movement of the cross-slide back and forth about six inches, whereby a small adjustment in the length of the stroke or the speed 40 of travel of the cross-slide can be accurately made to provide an extremely fine adjustment for the stroke of the ram.

The screw sleeve 23 is prevented from turning with the gear 22 by a key 61 which is removably secured to the plunge feed mechanism frame structure in a fixed position, and extends into a longitudinal slot 62 in the sleeve 23 (FIG. 3) so that sleeve 23 is reciprocated and moves the shaft 25 therewith by reason of the screw threaded connection thereto. The ram 15 has an end wall 63 formed with an opening 64 for receiving the shaft 25 and the shaft has a shoulder 65 thereon for engaging one side of the wall 63 to feed the ram towards the left as viewed, and the inner end of the shaft has a collar 66 screw threaded thereon and removably secured thereto by a pin 67 for engaging the other side of the wall 63 to retract the ram towards the right as viewed.

As the work wheel and/or regulating wheel wear down and are reduced in diameter, the end points of movement of the ram must be readjusted to enable the regulating wheel to properly engage the work. This is accomplished by loosening the collar 66 to free the shaft 25 for turning, turning the shaft by means of the hand wheel 38 to move the shaft by reason of its screw threaded connection in the sleeve 23 towards the left as viewed, and then securing the collar on the shaft to again secure the shaft to the ram.

As shown in FIG. 2, the length of the cross-slide stroke and the extent of movement in the direction to withdraw or retract the ram is adjusted by a member 75 slidably mounted for adjustment lengthwise on the cross-slide 20 at the rear end thereof for operating a ram advancing switch described hereinafter. By extending this member further outwardly than shown and securing it in its adjusted position by a screw 43, the return stroke of the air motor and the ram is shortened and the advance stroke commences again much sooner. For example, the normal return stroke of six inches can be shortened to two inches in cases where rapid automatic operation is desired.

The air motor 19 comprises a cylinder 39 mounted in fixed position above the cross-slide 20 and provided with conventional connections and valving for reversible operation of the motor, a slidable piston 49 in the cylinder, and a piston rod 41 extending outwardly of the cylinder and connected to a yoke 42 on the cross-slide.

The air motor 19 is adapted to effect rapid movement of the cross-slide 20 and the ram 15 in either direction, but as already indicated, provision is made for slowing down the speed of travel of the cross-slide in its direction to move the regulating wheel into engagement with the work. This is accomplished by a hydraulic fluid check 44 operatively connected to the cross-slide and mounted above the air motor cylinder 39.

The check 44, as shown in FIGS. 2 and 5, generally comprises a cylinder 45 having an opening 46 at one end and an opening 47 at its other end, a slidable piston 48 in the cylinder, a rod 49 connected to the piston and extending outwardly at one end above the air motor piston rod 41, a hydraulic fluid by-pass or transfer tube 50 connecting the openings 46 and 47, and an expansion chamber 51 acting as a reservoir for the fluid connected to the opening 47.

The check 44 and the air motor piston rod 41 are operatively connected by a stop 52 mounted near the free end of the rod 49 for lengthwise adjustment thereon, and an arm 54 secured at its lower end to the yoke 42 of the cross-slide 20 and having a lug 55 at its upper end formed with an aperture 56 through which the rod 49 extends, so that the cross-slide moves freely until the lug 55 engages the stop 52. As this occurs, the piston 48 which has hydraulic fluid at both sides thereof slows down the movement of the cross-slide and the inward movement of the ram 15. The point at which such slow down takes place during the outward movement piston rod 41 is determined by the position of the stop 52 on

the rod 49. The rate of slow down can be adjusted by a needle valve 56 in the transfer tube 50.

The rod 49 and the piston 48 thereon are returned or moved inwardly where the lug 55 engages a stop 53 secured to the rod 49 near the end of the cylinder from which rod extends when the piston is at the opposite end of the cylinder.

The chamber 51 comprises a cylinder 57, a slidable piston 58 in the cylinder, an opening 59 in the cylinder 10 at one side of the piston connected to the opening 47 and a spring 60 in the cylinder at the other side of the piston. In this manner the expansion chamber acts as a reservoir for the volume of fluid displaced by the piston 48 on its inward stroke (to the right as viewed), and 15 returns this amount to the cylinder 45 on the outward stroke (to the left as viewed), whereby the check 44 does not slow down the cross-slide 20 and the ram 15 during the return stroke.

In FIG. 6, a wiring diagram of the electrical control network for the air motor is shown which includes manually and automatically operated switches certain of which are also shown in FIG. 2, and a timer 70 for controlling the response of electrical components to the switch. Such a timer may be of the adjustable electronic type such as 25 a Bellows Model BDT 1 Timer which for the purpose of understanding the present invention need not be illustrated or described in detail.

More particularly, this network includes a manually operable starting switch 71 for causing the regulating 30 wheel to be advanced towards the work wheel, a manually operable switch 72 for causing the regulating wheel to be retracted, an automatic advancing switch 73 and an automatic retracting switch 74 both under the control of the air motor operated cross-slide 20 (this being accomplished 35 by the adjustable member 75 on the cross-slide 20 and a projection 76 on the arm 54 for respectively engaging these switches at the end of the retracting and advancing 40 strokes (FIG. 2), a switch 77 for connecting the switches 73 and 74 in the network for automatic cycling, and a solenoid 78 arrangement under the control of the switches 71, 72, 73 and 74 for controlling the valving (not shown) of the air motor to effect reciprocation thereof.

The timer 70 has terminals T1 to T10 to which the 45 switches and the relay are connected, as about to be described, and has terminals T and T' for connecting a source of electrical power.

The switches 71, 72 and 77 are of the single pole single 50 throw type and each have two terminals. One terminal of the switch 71 is connected to line A1 and its other terminal is connected to line A4; one terminal of the switch 72 is connected to line A1 and its other terminal is connected to line A3 and line AS3; one terminal of the switch 77 is connected to line A9 and line AS9 and its other terminal is connected to line A2.

The switches 74 and 73 comprise a pair of single pole double throw switches 79 and 80 and 81 and 82, respectively, each have three terminals with the pairs of switches being operable by members 83 and 84, respectively, connected to the switch arms but insulated therefrom and 60 controlled by the projection 76 and the member 75, respectively.

Only two of the terminals of the switch 79 are utilized and these are connected to lines AS3 and AS9, respectively. The terminals of the switch 80 are respectively connected to lines A10, A8 and A6. The terminals of the switch 81 are respectively connected to A5, A8 and A10. Only two of the terminals of the switch 82 are utilized and these are connected to lines A2 and A4, respectively.

The solenoid valve operating arrangement has three terminals which are respectively connected to lines S3, S7 and S4.

The lines prefixed A (automatic) and S (solenoid) are connected to terminals T of the timer of like number. 75 The lines AS3 and AS9 merely are connections for auto-

matic switching and are connected to the timer terminals by the lines A3 and A9. In view of this wiring identification system, it is not necessary to describe the path and connections of each line in greater detail. Certain of the common connections are made at the switch terminals as already indicated, and others are made through a terminal block 35.

In operation, the stop 52 and the member 75 are adjusted to determine the point at which the air motor is slowed down by the check 44 and the point at which the return stroke is terminated, respectively. The work wheel 12 and regulating wheel 16 are operated at the desired speed, a work piece is fed to these wheels, and operation of the plunge-feed mechanism 18 is controlled manually to test the machine for proper adjustment. After properly adjusting the machine by further adjustment of the hand-wheel 38, the stop 52 and the member 75, if required, the machine can be set for automatic repeated cycle operation.

The air motor 19 is operated manually to advance the ram 15 by closing the switch 71, which through the timer energizes the lines S4 and S7 and causes the solenoid arrangement to open a valve for admitting air at the right end of the cylinder 39 and move the piston 40, its rod 41 and the cross-slide 26 in the direction to advance the ram. At the end of this stroke the switch 71 is opened and the switch 72 is closed whereby lines S3 and S7 are energized through the timer to cause the solenoid arrangement to open a valve for admitting air at the left end of the cylinder 39 and move the piston 40, its rod 41 and the cross-slide in an opposite direction to retract the ram.

When the machine is to be operated automatically the switches 71 and 72 are open and the switch 77 is closed. Assuming that the air motor operated cross-slide 26 is in its retracted position (to the right as viewed, FIG. 2), the member 75 has moved the switch arms respectively connected to lines A8 and A2 of the switches 81 and 82 into engagement with contacts in lines A10 and A4. Lines A8 and A10 control an electronic time delay device for the lines A2 and A4 (S4) whereby operation of the air motor in the ram advancing direction is delayed. As the cross-slide 26 is moved towards the left as viewed, it is slowed down by the check 44, and at the end of this stroke, the projection 76 moves the switch arms respectively connected to lines AS9 (A9) and A8 of the switches 79 and 80 into engagement with contacts in lines AS3 (A3) and A10. Lines A8 and A10 again control the electronic time delay device but for the lines A3 (S3) and A9 whereby operation of the air motor in the ram retracting position is delayed to permit dwell of the regulating wheel for spark out of the ground work.

When lines A5 and A8 are connected by the switch 81, the time delay device is switched to affect the lines A3 (S3) and A9; and when the lines A6 and A8 are connected by the switch 80, the time delay device is switched to affect the lines A2 and A4 (S4), whereby a single time delay device controls the delay of the retracting and advancing strokes.

From the foregoing description, it will be seen that the present invention provides an improved plunge-feed control mechanism which has many advantageous features and is simple and economical in construction, has a minimum of mechanical parts, and is accurate and reliable in operation.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

I claim:

1. In a centerless grinder, the combination of a work wheel and a regulating wheel for receiving the work to be ground therebetween, a slidably mounted ram having said

regulating wheel mounted thereon at one end and having a horizontal longitudinally extending screw threaded shaft at its opposite end, a normally fixed block facing the last mentioned end of said ram, annular means journaled for rotation in a fixed position on said block, said block having central screw threaded means for cooperation with the threads of said shaft and having gear teeth on the periphery thereof, a cross-slide on said block, an elongate gear rack on said cross-slide having teeth in engagement with said gear teeth of said annular means for effecting rotation of said annular means to move said ram longitudinally upon crosswise movement of said cross-slide, power operated means having a stroke for directly effecting back and forth movement of said cross-slide through a relatively long stroke, said screw threaded means and said screw threads on said shaft having a pitch for effecting back and forth movement of said ram through a relatively short stroke whereby the ratio of the cross-slide stroke to the ram stroke is such that a small adjustment of the length of the stroke and speed of travel of said cross-slide can be accurately made to provide a fine adjustment of the stroke of said ram, a cross-slide mounting arrangement which comprises bushing means and a pair of rollers on said cross-slide, a rod on said block extending through said bushing means in sliding engagement therewith, and a rail on said block extending between said pairs of rollers and engaged thereby, whereby said cross-slide is maintained in a straight path to impart an even stroke to said ram.

2. In a centerless grinder, the combination of a work wheel and a regulating wheel for receiving the work to be ground therebetween, a slidably mounted ram having said regulating wheel mounted thereon at one end and having a horizontal longitudinally extending screw threaded shaft at its opposite end, a normally fixed block facing the last mentioned end of said ram, annular means journaled for rotation in a fixed position on said block, said block having central screw threaded means for cooperation with the threads of said shaft and having gear teeth on the periphery thereof, a cross-slide on said block, an elongate gear rack on said cross-slide having teeth in engagement with said gear teeth of said annular means for effecting rotation of said annular means to move said ram longitudinally upon crosswise movement of said cross-slide, power operated means having a stroke for directly effecting back and forth movement of said cross-slide through a relatively long stroke, said screw threaded means and said screw threads on said shaft having a pitch for effecting back and forth movement of said ram through a relatively short stroke whereby the ratio of the cross-slide stroke to the ram stroke is such that a small adjustment of the length of the stroke and speed of travel of said cross-slide can be accurately made to provide a fine adjustment of the stroke of said ram, a hydraulic check comprising a cylinder having its longitudinal axis parallel to the stroke of said cross-slide, a piston in said cylinder and a rod secured to said piston and extending outwardly of said cylinder, a stop adjacent the outer end of said rod, means on said cross-slide positioned for free movement lengthwise with respect to said rod and for engaging said stop near the end of the stroke of said cross-slide effecting infeed movement of said ram to slow down said cross-slide, whereby said regulating wheel on said ram initially moves rapidly towards said work wheel and said regulating wheel moves slower upon engagement of said stop by said cross-slide means, a switch on said block for controlling said power operated means to stop infeed movement of said cross-slide and to initiate return movement of said cross-slide, and an element on said cross-slide for actuating said switch near the end of the infeed stroke of said cross-slide.

3. A grinder according to claim 2, wherein the length of the stroke of said cross-slide is at least about ten times as great as the length of the stroke of said ram.

4. A grinder according to claim 2, wherein said stop and said rod include means for adjustably positioning said stop on said rod to determine the point at which said cross-slide is slowed down.

5. A grinder according to claim 2, wherein timing means control said switch for causing said ram to dwell at the end of its infeed stroke.

6. A grinder according to claim 2, wherein said rod has a second stop thereon engageable by said cross-slide means only near the end of its return stroke to reposition said rod. 10

7. A grinder according to claim 6, wherein said second stop and said rod include means for adjustably positioning said stop on said rod.

8. A grinder according to claim 2, including a second switch for controlling said power operated means to stop return movement of said cross-slide and to initiate infeed movement of said cross-slide, and means on said cross-slide for actuating second switch near the end of the return stroke of said cross-slide. 15

9. A grinder according to claim 8, wherein timing means control said second switch for causing said cross-slide to dwell at the end of its return stroke.

10. In a centerless grinder, the combination of a work wheel and a regulating wheel for receiving the work to be ground therebetween, a slidably mounted ram having said regulating wheel mounted thereon at one end and having a horizontal longitudinally extending screw threaded shaft at its opposite end, a normally fixed block facing the last mentioned end of said ram, annular means journalled for rotation in a fixed position on said block, said block having central screw threaded means for cooperation with the threads of said shaft and having gear teeth on the periphery thereof, a cross-slide on said block, an elongate gear rack on said cross-slide having teeth in engagement with said gear teeth of said annular means for effect- 30

ing rotation of said annular means to move said ram longitudinally upon crosswise movement of said cross-slide, power operated means having a stroke for directly effecting back and forth movement of said cross-slide through a relatively long stroke, said screw threaded means and said screw threads on said shaft having a pitch for effecting back and forth movement of said ram through a relatively short stroke whereby the ratio of the cross-slide stroke to the ram stroke is such that a small adjustment of the length of the stroke and speed of travel of said cross-slide can be accurately made to provide a fine adjustment of the stroke of said ram, said annular means including a sleeve slidably mounted in said block having internal threads cooperating with the threads of said shaft and having external threads, and a gear providing said gear teeth and having an internal threaded bore for cooperating with said external threads of said sleeve, manually operable means connected to said shaft for effecting rotation and longitudinal movement of said shaft 20 within said sleeve to adjust the position of said ram, means for releasably securing said shaft to said ram to normally prevent rotation of said shaft, and means for releasably securing said sleeve to said block to prevent rotation of said sleeve with respect to said gear.

11. In a grinder according to claim 10, including means for adjusting the length of the stroke of said power operated means to thereby directly adjust the length of the stroke of said cross-slide and proportionally adjust the length of the stroke of said ram. 25
